LAMP HOLDER

Frank D. Bryant, Stratford, and William R. Young, Fairfield, Conn., assignors to General Electric Company, a corporation of New York

Application September 18, 1940, Serial No. 357,262

11 Claims. (Cl. 173—356)

Our invention relates to lampholders for tubular electric lamps, such as fluorescent lamps of the well-known commercial type now in use.

An object of our invention is to provide a new and improved lampholder of the type described which is so constructed that the lamp may be locked in position within the holder against unauthorized removal.

In the accompanying drawing Fig. 1 shows a tubular lamp supported at each end by lampholders constructed in accordance with this invention; Fig. 2 is a view of the lampholder with the lamp pins mounted in position, a portion of the body of the lampholder being broken away; Fig. 3 is another view of the lampholder; Fig. 4 is still another view of the lampholder showing the means for releasing the lampholder from locking engagement with the lamp prongs; Fig. 5 is a sectional view through the lampholder taken along the line 5—5 of Fig. 4; Fig. 6 is a perspective view of a key for unlocking the lampholder, and Fig. 7 is a view of another form of key for unlocking the lampholder.

Referring to the drawing, we have shown a lampholder 10 of the type disclosed in the Marshaus Reissue Patent No. 21,545, assigned to the same assignee as the instant application, and which is adapted to support each end of a fluorescent lamp 11, in the manner shown by Fig. 1. The lampholder includes a base of insulating material 12 provided with a recess 13 for receiving spaced contact members 14. The contact members 14 are framed within an opening 15 in the housing merging with the recess 13; the opening is of generally circular formation and merges with a slot 16 extending to the upper edge of the housing. A stud 17 is upstanding from the bottom of the recess 13 and is provided with a diametrical slot 18 in alignment with the aforementioned slot 16. The contact members 14 cooperate with the center stud 17 in gripping the spaced connector prongs C of the fluorescent lamp to hold the lamp in position on the lampholder.

In mounting the lamp the connector prongs are moved in a line transversely to the axis of the lamp through the aligned slots 16 and 18 until the lower pin contacts the edge of the opening 15. Thereafter the lamp is rotated to move the contact pins into engagement with the contact members 14 to the position shown by Fig. 2. The connector prongs are guided into engagement with the contact members by the outer periphery of the stud 17 which may have curved surfaces corresponding to the wall of the open-

ing 15. The structure thus far described is the same as that disclosed in the aforementioned Marshaus patent and is one which is well adapted for the purposes intended in that it provides an effective electrical connection with the lamp prongs and holds the lamp securely in position without danger of the lamp becoming jarred loose from the holder.

In some cases, however, it is desirable to prevent unauthorized removal of the lamp. To this end, we provide means for locking the lamp prongs in position on the lampholder together with means for readily releasing the locking means so that the lamp may be removed from the lampholder. For this purpose each contact member 14 is provided with an indented portion 19 which is adapted to receive the connector prong of the lamp and which holds it securely in position against the outer periphery of the stud 17. Immediately adjacent the indented portion 19 are lugs 20 which are bent inwardly from the planes of the indentations 19 to form projecting edges which are disposed on opposite sides of the lamp connector prongs and which normally engage the outer periphery of the stud 17. After the lamp is rotated to move the connector prongs into seated position on the lampholder, they remain within the indentations 19 formed in the contact members between the opposed lugs 20. Seating of the connector prongs is readily attained due to the fact that as they are rotated within the opening 15 they move the flexible contact members 14 outwardly and then snap into position within the indentations 19 over the lugs 20. However, once the prongs are seated in the indentations rotation of them to remove the lamp is prevented due to the fact that they engage the abutment surfaces 20. This means that the contact members 14 cannot be sprung outwardly to release the connector prongs.

In order to release the connector prongs from engagement with the contact members, a key is provided which may be inserted into the lampholder to temporarily move the contact blades out of engagement with the connector prongs, so that the latter may be rotated within the lampholder to remove the lamp from the holder. Such a key is shown in Fig. 5 of the drawing. The key 25 is provided with a tongue 26 which is adapted to extend through the aligned slots 16 and 18 to position the key on the lampholder. Pivottally mounted on opposite sides of the key are operating levers 27 which are adapted to extend into the recess 13 into engagement with the respective contact blades 14. At their upper

ends the contact blades 14 are provided with outwardly bowed portions 28 forming bearing surfaces for engaging the levers 21.

It will be apparent from Figs. 2 and 3 that after the key is properly positioned on the lampholder it may be moved downwardly with the tongue 26 passing through the slots 16 and 18 so that the levers 21 engage the bearing portions 28 on the contact blades. Further movement of the key member forces the operating levers 21 downwardly past the bearing surfaces 28 to the position shown by Fig. 3. In this position the contact members are forced outwardly to an extent sufficient to move the locking projecting surfaces 20 out of the planes of the connector prongs of the lamp, so that the latter may be slightly rotated to move them out of the recesses 19. After the key is removed from the lampholder rotation of the connector prongs may be continued to move them to a position where they may be removed by lateral movement through the aligned slots 16 and 18.

A modified form of key structure is shown by Fig. 7. In this form the operating levers 21 are omitted and are replaced by cam surfaces 30, which engage the bearing surfaces 28 on the upper end of the contact blades and force these blades outwardly as the key is moved downwardly into the lampholder. In the form of the invention illustrated in Fig. 7 the recess 13 in the housing must be made sufficiently wide at the upper end to receive the cam 30.

While our invention has been illustrated and described as applied to a lampholder, such as shown by the aforementioned Marshaus patent, in which a slotted stud is positioned within the recess to guide the lamp prongs, it should be manifest that our invention is adapted for use equally as well in constructions in which the slot 18 is omitted or the stud 17 entirely omitted. In such cases the guiding tongue 26 would be unnecessary. The operating levers or cam surfaces would still engage the contact blades in the manner described.

Our invention is particularly useful in those cases where it is desired to lock the fluorescent lamp in position against the possibility of its being surreptitiously removed from the lampholder. This is accomplished simply by a slight change in the structure of the holder and the provision of a key for releasing the locking means. If desired, a locking lampholder may be placed at each end of the lamp. In most instances, however, a locking lampholder at one end of the lamp will be sufficient, the other end being supported by a lampholder of the type described in the Marshaus patent. This arrangement has the advantage that only a single key need be used and one hand is left free to rotate the lamp.

What we claim as new and desire to secure by Letters Patent of the United States is:

1. In combination, a base of insulating material having a recess in a face thereof merging with a slot extending to an edge of the base, spaced contact members in said recess and adapted to engage the spaced prongs of an electric lamp as the prongs are moved laterally through the slot and rotated within the recess into engagement with the contact members, said contact members being provided with means locking the pins in fixed position after they have been rotated into engagement with the contact members, and means insertable into said recess and cooperating with the spaced contact members to release them from engagement with the lamp

pins whereby the lamp may be withdrawn from the lampholder.

2. In a socket for use with a lamp having spaced contact pins, a base of insulating material having an opening therein and a slot extending from said opening to an edge of the base, spaced contact members in said opening, the lamp being mounted on said lampholder by moving the lamp pins laterally through the opening and rotating them into engagement with the contact members, means on said contact members for releasably locking the contact pins in seated position, and means cooperating with the contact members for releasing them from locked engagement with the lamp contact prongs.

3. A lamp socket for use with a lamp having spaced contact pins comprising, in combination, a base of insulating material having an opening therein and a slot extending from the opening to an edge of the base, spaced contact members within said opening and adapted to receive the lamp prongs as the latter are moved laterally through the slot and rotated into engagement with the contact members, said contact members being provided with means for locking the lamp prongs in seated position, and means insertable into the lampholder including cam surfaces for engaging the contact blades for moving them out of locking engagement with the lamp prongs.

4. A lamp socket for use with a lamp having spaced contact prongs comprising, in combination, a base of insulating material having an opening therein and a slot extending from said opening to a wall of the base, guiding means positioned within said opening, spaced flexible contact members within said opening on opposite sides of said guiding member, for receiving the lamp prongs as the latter are moved laterally through the slot and rotated within the opening into engagement with the contact blades, said contact blades being provided with projecting portions for locking the lamp prongs in seated position on the lampholder, and means cooperating with the contact blades to move them out of locking engagement with the lamp prongs.

5. A lampholder for use with a lamp having spaced contact prongs comprising, in combination, a base of insulating material having an opening in a face thereof and a slot extending from the opening to an edge of the base, spaced contact members in said opening, each contact member being provided with a recess and an adjacent projecting portion, the lamp prongs being adapted to be moved laterally through the slot and rotated into engagement with the contact blades to seated position within the recesses, the projecting portions on the contact blades maintaining the prongs in seated position within the recesses and means for moving the projecting portions out of locking relationship with the lamp prongs so that the latter may be rotated out of engagement with the contact blades.

6. A lamp socket for use with a lamp having spaced contact prongs comprising, in combination, a base of insulating material having an opening in one face thereof and a slot extending from the opening to an edge of the base, guide means within said opening provided with a groove in alignment with said slot, spaced flexible contact blades disposed in said opening on opposite sides of said guide member, the lamp prongs being seated in said lampholder by lateral movement through said aligned slot and groove for rotation within the opening into engagement with the contact blades, each contact blade being pro-

vided with a recess for receiving the lamp prongs in seated position, and a projecting portion for locking the lamp prongs within the recesses, and means insertable into the lampholder for engaging the contact blades to flex them outwardly whereby the projecting portions are removed from locking relationship with the lamp prongs to permit rotation of the prongs out of seated position in the lampholder.

7. A locking lamp socket for use with a key and a lamp having spaced contact prongs comprising, in combination, a base of insulating material having an opening in a face thereof and a slot extending from the opening to an edge of the base, spaced contact members mounted in said opening, each contact member being provided with a recessed portion and a projecting portion adjacent the recess whereby the lamp prongs may be moved laterally through the slot and rotated within the opening into engagement with the contact blades, rotation of the contact prongs flexing the contact blades outwardly to permit the prongs to be seated within said recesses and locked therein by cooperation with said projecting portions, and means for flexing said contact blades outwardly for removing said projections from locking relationship with the lamp prongs whereby the latter may be rotated out of engagement with the contact blades to remove the lamp from the lampholder.

8. In a socket for use with a lamp having spaced contact pins, a base of insulating material having an opening therein and a slot extending from said opening to an edge of the base, spaced contact members in said opening, the lamp being mounted on the socket by moving the lamp contact pins laterally through the opening and rotating them in either direction into engagement with the contact members, and means for positively locking the contact pins in seated position to prevent rotation of the lamp in either direction.

9. A locking lamp socket for use with a key and a lamp having spaced contact prongs comprising, in combination, a base of insulating material having an opening in the base thereof and

5 a slot extending from the opening to an edge of the base, spaced contact members mounted in said opening, each contact member being provided with a recessed portion and a projecting portion adjacent the recess whereby the lamp prongs may be moved laterally through the slot and rotated within the opening into engagement with the contact blades, rotation of the contact prongs flexing the contact blades outwardly to permit the prongs to be seated within said recesses and locked therein by cooperation with said projecting portions, and means for flexing said contact blades outwardly for removing said projections from locking relationship with the lamp prongs.

10. A locking socket for use with a key and a lamp having spaced contact prongs comprising, in combination, a base of insulating material having an opening therein and a slot extending from said opening to an edge of said base, spaced contact members in said opening, the lamp being mounted on said lampholder by moving the lamp pins laterally through the opening and rotating them into engagement with the contact members, and means on said contact members for positively locking the contact pins in seated position, the contact members being adapted for cooperation with the key to release the lamp contact prongs from locking position.

11. In a locking socket for use with a key and a lamp having spaced contact pins, a base of insulating material having an opening therein and a slot extending from said opening to an edge of the base, spaced flexible contact members in said opening, provided with locking means for engaging the lamp contact pins, the lamp being mounted on the socket by moving the lamp laterally through the opening and rotating it into engagement with the contact members to flex them, said contact blades being flexed upon cooperation with the key for releasing the lamp pins from locking engagement with the contact members.
